ABSTRACT: A releasable lariat honda having a pair of fingers extending from a yoke or body. At least one of the fingers is segmented and has loading means associated therewith whereby the finger tips of the honda are urged toward each other. The yoke holding the pair of fingers has a stem extending rearwardly therefrom. Said stem defines a bore which extends through the yoke and has a longitudinal axis which extends through the point of intersection of the fingertips. The stem and the yoke are adapted to holdingly receive a lariat. In the preferred embodiment, the stem defines a helix, which helix is carried through the yoke on one side.

1
LARIAT HONDA

My invention relates to an improved lariat honda, and more particularly to a lariat honda adapted for quick release for use in practice roping.

Individuals learning to rope animals generally start their instructive period by learning to cast a loop, formed in a lariat, about a stationary object. In the past, upon successful casting of the loop, it was necessary for the individual to approach the target and remove the loop therefrom. It is apparent, therefore, that a honda which will release the loop from the target without the necessity of the individual approaching the target will permit a larger number of successful casts in a given period of time.

Releaseable hondas previously attempted were generally complex of manufacture, heavy in weight, or dependent upon the natural resiliency of the material of construction. Further, previous devices generally required that the rope be specially adapted to be secured to the honda.

The principal object of my invention is to provide a lightweight lariat honda which is easily attached to a lariat and which may be quickly released during practice roping without the user approaching the target object.

It is another object of my invention to provide an improved lariat honda which is relatively inexpensive and simple of manufacture.

Other objects and advantages of my invention will become apparent in the course of the following specification and claims when taken in view of the accompanying drawings in which:

FIG. 1 is an isometric of one embodiment of my invention;

FIG. 2 is a plan view of one embodiment of my invention with a schematic representation of a lariat as it is functionally employed with my invention.

FIG. 3 is a partial view, illustrating an alternative means for releaseably holding a lariat within the aperture formed by the honda of my invention; and

FIG. 4 is a partial sectional view taken along 4-4 of FIG. 3.

With reference now to the drawings, and particularly the FIGS. 1 and 2, my improved lariat honda comprises a yoke 10, a pair of fingers 11, and a stem 12. The fingers 11 extend forwardly from the yoke 10 and contact one another at their tips 14, thereby forming an aperture through which a lariat 15 may pass. At least one of the fingers 11 is segmented. The segments are hingedly joined at the knuckle 16, the movable segment 17 pivoting about the pin 18 which passes through the stationary portion of the segmented finger 11. A spring 19 is secured to the stationary segment of the finger 11 and engages the movable segment 17, thereby urging said movable segment 17 to pivot about the knuckle 16 so that the fingertips 14 are maintained in contact.

Spring 19 is secured to the stationary portion of the finger 11 by a screw 20. If desired, additional threaded apertures 22 may be provided so that the pressure of the spring 19 on the movable segment 17 of finger 11 is adjustable by moving the point at which the spring is secured to the stationary portion forwardly or rearwardly.

As illustrated in the drawings, the fingers 11 taper from their juncture with the yoke 10 to their narrowest portion at their tips 14. If desired, both fingers 11 may be segmented. Segmenting of both fingers provides the additional advantage of uniformity in separation of the fingertips when a target has been lassoed and the operator desires to release the rope or lariat from the honda.

Stem 12 is integral with the yoke 10 and extends rearwardly therefrom. Stem 12 defines a bore 23 whose longitudinal axis extends through the point of intersection of the fingertips 14. Stem 12 has a helical shape, which helix is carried through the yoke 10 on one side. The lariat 15 is provided with a thickened portion illustrated, for convenience in the accompanying drawings, as a knot 24. To secure the honda to the lariat, the rope or lariat 15 is simply laid across the open portion of the helix with the thickened portion 24 of the lariat within the aperture defined by the yoke 10 and the fingers 11 of the hon-

2

da. Straightening of the lariat 15 in the bore 23 completes assembly of the lariat and honda. Disassembly is equally simple, being the reverse of the foregoing.

I prefer to construct my honda of cast aluminum alloy or similar lightweight material. For example, the various magnesium alloys could be advantageously employed. Further, if desired, the honda may be machined from solid material, but ordinarily this would be prohibitive in cost.

After the lariat 15 has been assembled with the honda, the fingertips 14 of the honda are forced apart and a portion of the lariat is inserted into the aperture defined by the yoke 10 and the fingers 11 of the honda. The loop thus formed is cast at the target, the loop passing over or around the target. By pulling on the lariat, the fingers 11 are forced apart at their tips 14 and the lariat 15 is released for recovery by the individual practicing roping.

FIGS. 3 and 4 illustrate an alternative embodiment of my invention which modifies the structure somewhat, but embodies

20 the same principle. Stationary segment 30 and movable segment 31 are pivotally joined at a knuckle and rotate about pin 34. The movable segment 31 has a rearwardly extending lever 35 which extends along the inner surface of the stationary segment 30. Rubberband means 36 resiliently urges said lever 35 toward the inner side of said stationary segment 30. In this manner, the fingertips of the honda are urged toward each other. Adjustment in the loading of the fingertips toward each other may be made by varying the size or number of rubberbands or rubber rings 36.

30 My improved lariat honda is easily secured to and detached from a lariat. Thus, the person practicing roping need not have a plurality of lariats, but can use same lariat for practice and for work. Further, release of a practice loop from the target is simply and easily accomplished by a tug on the lariat, obviating the need to approach the target after each successful cast.

Various modifications may be made in my invention without departing from the spirit or scope thereof, and it is to be understood that I limit myself only as defined by the appended claims.

I claim:

1. An improved lariat honda comprising a yoke, a pair of fingers and a stem, said fingers extending forwardly from said yoke and arched to touch at their tips, thereby defining an aperture to pass a lariat, at least one of said fingers being segmented, said segments pivotally joined at a knuckle, said segmented finger having resilient loading means associated therewith whereby the segment remote from said yoke is urged to pivot about said knuckle toward the tip of the other finger, said stem extending rearwardly from said yoke and defining a bore, said bore passing through said stem and through the body of said yoke, the longitudinal axis of said bore extending through the point of contact between said fingers, said stem adapted to holdingly receive a lariat end having a thickened portion.

2. The improved lariat honda of claim 1 wherein said stem defines a helix, said helix being carried through said yoke on one side.

3. The improved lariat honda of claim 2 wherein both of said fingers are segmented and said loading means associated with the segments remote from said yoke is adjustable.

4. The improved lariat honda of claim 1 wherein both of said fingers are segmented.

5. The improved lariat honda of claim 1 wherein said resilient loading means is adjustable.

6. The improved lariat honda of claim 1 wherein said loading means comprises a spring secured to the stationary portion of each segmented finger.

70 7. The improved lariat honda of claim 6 wherein said spring is secured to said stationary portion by screw means and said stationary portion defines a plurality of threaded apertures whereby the point at which said spring is secured to said stationary portion may be moved forwardly or rearwardly, thereby to adjust the loading on said movable segment.

8. The improved lariat honda of claim 7 wherein said stem defines a helix, said helix carried through said yoke on one side.

9. The improved lariat honda of claim 1 wherein the movable segment of each segmented finger has a rearwardly extending lever extending along the inner surface of the stationary segment and rubberband means is positioned to urge said

lever toward the inner side of said stationary segment, thereby urging the tips of said fingers toward each other.

10. The improved lariat honda of claim 9 wherein said stem defines a helix, said helix carried through said yoke on one side.
